UNITED STATES PATENT OFFICE

SAMUEL HERBERT MAW, OF TORONTO, ONTARIO, CANADA, ASSIGNEE TO THE T. MATON COMPANY, LIMITED, OF TORONTO, ONTARIO, CANADA

LIGHTING FIXTURE

Application filed October 13, 1930. Serial No. 488,436.

The principal objects of this invention are to effect a uniform diffusion of light and to effect the distribution of light rays around the fixture in such a manner as to materially 5 reduce the appearance of bulkiness or massiveness of the fixture.

The principal features of the invention consist in the novel construction and arrangement of light reflecting and light diffusing surfaces in relation to the light whereby diffused light is directed downwardly and reflected light is directed upwardly and outwardly to illuminate and reflect from the major portion of the outer surface of the fixture whereby such surfaces are rendered luminous.

In the accompanying drawings, Figure 1 is a perspective view of my improved pendant fixture.

20 Figure 2 is an enlarged part elevation and part sectional detail of the fixture.

In the construction of fixture herein shown a lamp holder 1 is suspended by a plurality of light rods 2 from the supporting flange 3 which is adapted to be secured to or against the ceiling.

25 A light sheet metal shield 4 somewhat in the form of the frustum of a cone and having a concaved outer surface, is suspended in a suitable manner from the lamp holder 1 by the rods 5. The lower and smaller diameter edge of the shield 4 is formed with a narrow flange 6 to which are secured a plurality of connecting rods or brackets 7 which are secured to the inner wall of a substantially frustro-conical member 8, the outer surface of which is concaved.

The upper beaded or rolled edge 9 of the member 8 is arranged substantially in horizontal alignment with the lower flanged edge 6 of the upper frustro-conical member 4 and a clear space is arranged between the two members. The bottom edge of the frustro-conical member 8 is flanged inwardly and presents a frustro-conical surface 10 sloping upwardly and inwardly.

30 Mounted upon and rigidly secured to the upper edge of the portion 10 of the member 8 is a reflector member 11 which has a curved reflecting surface arranged in a substantially

horizontal position and extending between the inner flanged edge of the member 8 and the inner surface of the concaved frustro-conical portion. This reflecting surface is so arranged that rays of light emanating from the lamp 12 are reflected upwardly inside of the frustro-conical shield 4 and also outside of the same and they are directed upwardly from this reflecting surface to strike the frustro-conical concaved outer surface of the shield 4 which is formed of highly polished metal.

The inward portion 12 of the reflector member 11 is flanged upwardly in a substantial continuation of the inner frustro-conical portion 10 of the member 8 and it is provided with a horizontal flange 13 which supports the rim of a translucent glass 14 which is of a shallow inverted bowl form. This glass permits light rays emanating from the lamp to pass therethrough in a diverging downward direction and the inner rims 10 and 12 are highly polished and reflect the rays of light passing downwardly through the peripheral portion of the glass 14.

35 A plurality of bracket arms 15 are supported upon the horizontal flange 13 and extend about the inverted bowl-shaped glass 14 and carrying at the upper ends laterally flanged portions 16 upon which is mounted an open-bottomed semi-bowl shaped glass ring 17 which is coated on the outer side with a suitable reflecting material such as silver.

The reflecting surface of the inner mirror glass directs rays of light emanating from the lamp both downwardly and upwardly, those rays being directed downwardly passing through the glass 14, while those directed upwardly illuminate the reflecting surface of the lamp holder 1 and also pass to be redirected downwardly from the ceiling.

40 It will be readily understood that the light rays emanating from the lamp will be spread outwardly, both upwardly and downwardly, both from the inside and from the outside, and the outer curved surfaces of the fixture which are of a highly reflective nature will be attractively illuminated.

A fixture such as described is very light in weight and is therefore very easily sus-

pended, the amount of glass therein being reduced to the minimum.

What I claim as my invention is:—

1. A lighting fixture comprising a metallic shield surrounding a lamp and having interior and exterior reflecting surfaces, light-diffusing means arranged below the lamp enclosing the opening in the said shield and a reflector member forming an outward continuation of said light diffusing means spaced below said shield and directing rays from the lamp upwardly to either side of said shield.

2. A lighting fixture comprising a pair of spaced substantially frustro-conical shields supported in position in spaced relation to a lamp, one of said shields extending above the other, a translucent glass carried by the lower shield, and means for reflecting rays of light emanating from the lamp upwardly to the inside and outside of the upper shield.

3. A lighting fixture comprising, a substantially frustro-conical metallic shield having a polished exterior surface, a substantially frustro-conical metallic shield suspended below the aforesaid shield and spaced therefrom, a reflecting surface arranged within the latter shield adapted to direct rays of light upwardly around the exterior of the upper shield, a translucent glass extending across the lower shield, and a reflector member arranged between the lamp and the upper shield and having curved reflecting surfaces adapted to direct rays of light both upwardly and downwardly, said reflector member being spaced above said translucent glass to permit the passage of direct light rays to said reflecting surface.

4. A light fixture, comprising a metallic shield of substantially frustro-conical form having a concaved outer face, a metallic shield of substantially frustro-conical form suspended from the aforesaid shield and spaced therefrom, a curved reflecting surface substantially horizontally arranged within the latter shield and adapted to direct rays of light upwardly to the inside and the outside of the upper frustro-conical member, translucent glass diffusing means supported from the lower shield member, a reflecting shield spaced above the lower shield and arranged within the upper shield, and a lamp supported within the upper shield.

5. A lighting fixture comprising a lamp holder adapted to be suspended from the ceiling, a circular metal shield of substantially frustro-conical form suspended from the lamp holder and spaced therefrom, a substantially frustro-conical metal ring suspended from said shield and spaced from its lower edge, said lower ring having an inwardly and upwardly convergent wall, a reflector member supported in a substantially horizontal position within the lower suspended member and having an inwardly and upwardly sloping wall and a horizontal flange, an inverted

bowl-shaped translucent glass mounted on said flange, a ring-shaped curved reflecting member supported above the flange of the aforesaid reflecting member, and a lamp in the holder arranged centrally above the inverted bowl-shaped member and centrally within said reflecting member and directing rays of light below the encircling reflective member upon the surface of the horizontal reflecting member to be redirected upwardly between the lower outer metallic member and the frusto-conical shield and to reflect from the outer surface of said upper shield.

6. In a lighting fixture, the combination with a light source, of an upwardly and outwardly flaring shield encircling said lamp, a reflector encircling said light source within said shield and adapted to intercept outwardly directed rays and direct same upwardly or downwardly, and a reflector spaced below said encircling reflector, said reflector being positioned to receive rays passing laterally below said encircling reflector and direct the same upwardly to either side of said flaring shield.

7. In a lighting fixture, the combination with a light source, of an upwardly and outwardly flaring shield encircling said lamp, a reflector encircling said light source within said shield and adapted to intercept outward rays and direct same upwardly and downwardly, a reflector spaced below said encircling reflector, said reflector being positioned to receive rays passing laterally below said encircling reflector and direct the same upwardly to either side of said flaring shield, and a translucent glass supported within said second-mentioned reflector and receiving the downwardly directed light rays, said glass and encircling reflector being spaced apart to provide a passage for the light rays in alignment with said light source and the second-mentioned reflector.
